[57] ABSTRACT

Valuable aromatic hydrocarbons are produced from a hydrocarbon feedstock particularly rich in C_8 + aromatics. The feedstock is initially fractionated into (a) a first stream consisting mainly of benzene, toluene and non-aromatics boiling in the same temperature range along with a minor proportion of C_8 aromatics, (b) a second stream consisting mainly of C_8 aromatics, and (c) a third stream consisting predominantly of C_9 and C_{10} aromatics. Stream (a) is subjected to solvent extraction to obtain a non-aromatic raffinate and an aromatic extract, which latter is distilled to obtain as products benzene, toluene and a C_8 aromatics fraction. Stream (b) may be utilized as such or extractively distilled to remove any nonaromatic hydrocarbon impurities which may be present. Stream (c) may, if desired, be separated into a C_9 fraction and a C_{10} fraction with the former being hydrodealkylated to yield additional quantities of benzene, toluene and C_8 aromatics.

4 Claims, 1 Drawing Figure

PRODUCTION OF AROMATIC HYDROCARBONS

BACKGROUND OF THE INVENTION

a. Field of the Invention

The invention relates to the production of aromatic hydrocarbons from hydrocarbon feedstocks rich in aromatics. More particularly, it relates to fractionation of such mixtures prior to solvent extraction thereof.

b. Prior Art

Heretofore, a number of solvent extraction processes have been proposed and put into practice for the recovery of aromatic hydrocarbons such as benzene, toluene and C₈ aromatics from hydrocarbon mixtures containing such aromatic components. A typical example of such solvent extraction is the process in which an aromatics-containing feedstock is separated into raffinate and extract; the latter, being a stream essentially of pure aromatics, is then fractionated into benzene, toluene and C₈ aromatics, respectively, while higher boiling aromatic hydrocarbon fractions (C₉+) may be, if desired, subjected to dealkylation to form benzene, toluene and C₈ aromatics and recycled for the fractionation and purification.

Processes of the type just referred to as in conventional practice have the disadvantage that C₈ aromatics, C₉ and C₁₀ aromatic hydrocarbons, in particular, are difficult to recover in commercially satisfactory yields without the use of extravagant quantities of solvents and thus without resort to increased operation and utility costs. Moreover, with these prior-art processes it has been quite difficult to obtain the desired C₈, C₉ and C₁₀ aromatics at any higher yield than 95 percent, 70 percent and 50 percent, respectively, depending upon the feedstock composition even with the use of large quantities of solvent.

SUMMARY OF THE INVENTION

The present invention owes its merits to the discovery, after exhaustive research of the relations between given classes of aromatic hydrocarbon compounds and solvents for the selective extraction thereof, that there may be obtained superior results from isolating C₈ aromatics, C₉ and C₁₀ aromatics by fractionation from the starting material prior to charge to the extraction stage thereby making it possible to provide high yields of these aromatics fractions as well as substantial increases in the yields of benzene, toluene, and especially C₈ aromatics with a minimum of solvent and extract-recycle requirement.

Briefly summarized, the present invention comprises a process wherein a feedstock consisting of aromatics-containing hydrocarbon mixtures is subjected to fractional distillation in a splitter without first charge to a liquid-liquid extraction stage and separated into a first fraction consisting of the major portions of benzene, toluene and non-aromatics boiling at the same range and a minor proportion of C₈ aromatics, into a second fraction consisting of mainly C₈ aromatics, and into a third fraction consisting predominantly of C₉ and C₁₀ aromatics and wherein the said first fraction is further subjected to liquid-liquid extraction, the extract thereby obtained being fractionated and purified into final benzene, toluene and C₈ aromatics products. The said second fraction may be utilized per se as a material for suitable chemical processing or as end product C₈ aromatics. Alternatively, it may be, if desired, extractively distilled to provide high-purity C₈ aromatics. The

raffinate containing a minor proportion of C₈ aromatics and non-aromatics is taken overhead from the extractive distillation column and may be recycled to the liquid-liquid extraction stage. The said third fraction may be dealkylated together or after it is separated into C₉ and C₁₀ aromatics fractions, which C₉ aromatics may be converted suitably into benzene, toluene and C₈ aromatics. The thus obtained dealkylates may be joined with the aromatics extract stream from the liquid-liquid extraction stage and charged to the benzene, toluene and C₈ aromatics fractional distillation stages hereinafter described.

The main fractional distillation employed at the beginning of the process according to the invention for splitting the starting feedstock into three different fractions may be carried out in a variety of modes of operation depending upon the particular feedstock composition used. A typical embodiment involves subjecting the feedstock to fractional distillation in a splitter of known type where the major proportions of benzene, toluene, non-aromatics and a minor proportion of C₈ aromatics are taken as a first fraction or stream from the top of the splitter for introduction as a charge to liquid-liquid extraction stage to recover benzene, toluene and C₈ aromatics, and subjecting the bottoms product of the splitter consisting of the major proportions of C₈ aromatics and C₉ and C₁₀ aromatics to distillation thereby obtaining C₈ aromatics as a second stream from the overhead of the distillation column, said second stream consisting mainly of C₈ aromatics and non-aromatics of the same boiling range, and C₉ and C₁₀ aromatics as a third stream from the bottom of the column.

Another embodiment consists in separating the feedstock by distillation into an overhead product consisting of benzene, toluene and C₈ aromatics and a bottoms product as a third stream consisting predominantly of C₉ and C₁₀ aromatics, and in further separating said overhead product by distillation into a first stream (overhead product) consisting mainly of benzene, toluene and non-aromatics of the same boiling range and trace amounts of C₈ aromatics and a second stream (bottoms product) predominantly of C₈ aromatics.

Another embodiment comprises separating the feedstock by distillation under selected conditions to obtain the first, second and third streams, respectively, from the top, middle and bottom of a single distillation column.

Any combination of the foregoing embodiments relative to the main fractionation of a feedstock may be chosen in accordance with a specific feed composition, and each fractional distillate may be adjusted in composition and flow rate in a manner desired to effectively accomplish the subsequent unit processing.

Accordingly, it is an object of the present invention to eliminate the above-noted difficulties of the prior-art processes.

Another object of the invention is to provide a new, useful process for the separation and purification of aromatic hydrocarbons which can be carried out with desirably reduced solvent ratios related to total starting material and in greater yields than anticipated by the conventional processes.

Still another object of the invention is to provide a new, useful process capable of recovering increased yields particularly of C₈, C₉ and C₁₀ aromatic hydrocarbons in addition to benzene and toluene.

These and other objects and features of the invention will be apparent to those skilled in the art from the following description and claims taken in connection with the accompanying drawing.

BRIEF DESCRIPTION OF THE DRAWING

The drawing is a diagrammatic illustration of an embodiment of the invention and includes modifications thereof.

DESCRIPTION OF THE PREFERRED EMBODIMENTS

The process of the invention will now be discussed in further detail with reference to the accompanying drawing which is utilized to particularly explain that mode of operation which employs the combination of a splitter and a C₈ aromatics distillation column. The other processing techniques referred to hereinabove may, of course, be employed with similar results.

The aromatics-rich feedstock suitable for the invention may be hydrocarbon mixtures available typically from catalytic reformates, hydrogenated pyrolysis gasoline, crude benzole and mixtures thereof. It is to be noted, however, that the invention proves its outstanding advantage over any prior-art processes in that a starting feedstock containing over 10 percent of C₈ aromatics can be processed with success.

The reference numeral 1 designates a feed line for charging the starting material to a splitter 2, which is operated under selected temperature conditions to produce trace amounts of C₈ aromatics in the overhead with the major portions of C₈ aromatics in the bottom. Such temperature conditions will be shown in the Example which appears hereinafter. From the top of this splitter column are taken as overhead via line 3 benzene, toluene and non-aromatics of the same boiling range, as well as a minor proportion of C₈ aromatics. The major proportions of C₈, C₉ and C₁₀ aromatics and non-aromatics are withdrawn via line 16 from the bottom of the splitter 2.

Now, the overhead stream from the splitter 2 is charged, via line 3, to a solvent extraction unit 4 where it is treated in well-known manner and separated into benzene, toluene, C₈ aromatics and non-aromatics. More specifically, this unit 4 consists of a multi-stage counter-current extractor, an extract-recycle column, a solvent stripper and auxiliary equipment. Preferably, the stream fed via line 3 is charged to the middle section of the extractor and a solvent enters the top thereof so that the solvent descends in counter-current contact with the ascending aromatics-rich hydrocarbon.

In the extraction unit 4, the non-aromatic fraction is withdrawn as a raffinate via line 5 and the aromatics extract is charged via line 6 to an aromatics fractionation system. Since the feed to be charged to the extraction unit contains, in addition to benzene and toluene, a minor part of C₈ aromatics but no C₉ or C₁₀ aromatics, the selectivity of the solvent is greatly enhanced.

The solvents for use in liquid-liquid extraction according to the invention include N-methylpyrrolidone, N-hydroxyethylpyrrolidone, butyrolactone, ethylene or diethylene glycol, dimethylformamide, sulfolane, dimethylsulfoxide and the like or mixtures thereof. These solvents may be used solely or in mixtures thereof, or may be diluted with water or organic solvents with a low aromatics capacity to improve the selectivity of

those mixtures and preferably have a higher boiling point than the aromatics to be recovered.

As already stated, the overhead product of the splitter 2 is substantially free of C₉, C₁₀ and other higher boiling materials including only trace amounts of C₈ aromatics, which results in reducing the amount of solvent required for the extraction of benzene, toluene and C₈ aromatics. This, together with reduced ratios of solvent to feed, is another important aspect of the invention, as will be noted specifically in the example hereinafter given.

The aromatics distillates may be treated with clay, in a known manner, to remove the olefins and impurities which may be present. Thereafter they are forwarded through line 6 to the aromatics fractionation system. At the same time, a product stream from the dealkylation unit may be supplied to this system via line 26.

The aromatics fractionation system consists of a benzene distillation column 7, a toluene distillation column 10 and a C₈ aromatics distillation column 13. The aromatics extract is charged through line 6 to the benzene distillation column 7 wherein pure benzene is separated and taken as liquid a few trays below the top tray. The bottoms stream consisting of toluene and minor parts of C₈ aromatics is introduced, via line 9, to the toluene distillation column 10. Pure toluene is drawn off as liquid a few trays below the top tray of column 10, via line 11. The bottoms, consisting of pure C₈ aromatics, are withdrawn via line 12. Unlike the conventional processes, the charge to the toluene column 10 is very low in C₈ aromatics content with the result that toluene is easily and effectively separated from C₈ aromatics.

The bottoms product from the toluene distillation column 10 consists essentially of pure C₈ aromatics and hence may be utilized, *per se*, as a chemical processing material or as an end-product. However, it may be, if desired, further processed in a first C₈ aromatics distillation column 13, from the top of which column, via line 14, there may be obtained pure C₈ aromatics. The bottoms of this column 13, withdrawn from line 15, contains small amounts of higher boiling impurities produced from the dealkylation unit. The C₈ aromatics in line 12 may be alternatively sent via line 31 to a second C₈ aromatics distillation column 17 later described. It will be appreciated that ultimate purity of the desired aromatic hydrocarbons may be improved by recycling some slip streams from the benzene and toluene column tops to the solvent extraction unit 4. Yields of the various aromatics recovered therein are illustrated in relation to starting feed and compared with those obtainable by prior-art in the following example.

The bottoms product of the splitter 2 is withdrawn, via line 16, and charged to a second C₈ aromatics distillation column 17 where C₈ aromatics are separated and taken overhead via line 18. C₉ and C₁₀ aromatics are withdrawn as bottoms via line 22. Preferred temperature conditions for this column are about 140°-150°C. The C₈ aromatics taken from the top of the column 17 may be of a quality suitable for immediate use as a chemical processing material or as an end-product. However, where utmost purity is desired, the C₈ aromatics may be clay-treated and forwarded to an extractive distillation unit 19 to remove objectionable non-aromatic hydrocarbon impurities.

More specifically, the C₈ aromatics fraction is directed substantially to the lower part of the extractive

distillation unit or column 19, while recycled solvent is fed to the top thereof. The column 19 is operated under selected conditions to allow a mixture containing the non-aromatics in the C₈ aromatics fraction and small amounts of C₈ aromatics to pass in vapor phase out through the overhead of the column. The bottoms from this column consist essentially of C₈ aromatics and solvent and are sent to a C₈ aromatics stripper (not shown) where pure C₈ aromatics and solvent are withdrawn from the top and bottom, respectively; the solvent being further recycled to the extractive distillation unit 19.

The extractive distillation may be conducted preferably with a polar solvent boiling above the C₈ aromatics and especially one forming no azeotropes with the hydrocarbons contained in the C₈ aromatics. Suitable solvents for this purpose are N-methylpyrrolidone, sulfolane and polyethylene glycol. These solvents may be advantageously used for both extractive distillation and liquid-liquid extraction. Such solvents as may form azeotropes with the hydrocarbons in the C₈ aromatics stream may also be used if there is a suitable solvent recovery unit provided. This extractive distillation gives as another overhead product a raffinate consisting of the non-aromatics contained in the C₈ aromatics which may be withdrawn, via line 21, and charged together with the stream in line 3 to the extraction unit 4 for recovery of the small amounts of C₈ aromatics contained therein. The C₈ aromatics is thus purified to less than 500 p.p.m. of non-aromatics content and is withdrawn via line 20.

Where the liquid-liquid extraction and the extractive distillation are combined with a hydrodealkylation process, the C₈ aromatics stream withdrawn from the bottom of the toluene distillation column 10 may be charged via lines 31 and 16 to the second C₈ aromatics distillation column 17 to separate high boiling materials formed during the hydrodealkylation later described. Alternatively, these bottoms may be treated in the first C₈ aromatics column 13. The C₉ and C₁₀ aromatics fraction which has been withdrawn from the bottom of the second C₈ aromatics column and which contains small amounts of non-aromatics, may be, if desired, charged via line 22 directly to the hydrodealkylation unit 25 for conversion to benzene, toluene and C₈ aromatics, and thereafter passed from line 26 to line 6 and thence into the aromatics fractionation system. For better results, the C₉ aromatics fraction may be separated from the C₁₀ aromatics prior to such hydrodealkylation. In which instance, the bottoms stream from the second C₈ aromatics column 17 is forwarded via line 22 to a C₉ aromatics distillation column 23 therein to separate and remove C₁₀ aromatics and to take C₉ aromatics overhead for introduction through line 24 to the unit 25. This hydrodealkylation process is well known and conducted in the presence of hydrogen and catalyst or thermally in the absence of catalyst.

Typically, the catalytic hydrodealkylation is performed preferably at about 500°C-800°C, under 35-76 Kg/cm²g. and in the presence of hydrogen and known catalysts such as chrome-alumina, nickel, cobalt oxide and molybdenum oxide. These operating conditions are such that small amounts of C₉ and C₁₀ paraffins undergo decomposition and turn into low molecular weight gases, while C₉ and C₁₀ aromatics become progressively demethylated and converted to benzene, toluene and C₈ aromatics. The thermal dealkylation takes

place under similar or somewhat higher temperature and pressure conditions and in the presence of hydrogen, but without catalysts.

The following example is illustrative of operation of the process in accordance with the invention, with the flow rates given in metric tons/hr. (t/hr).

The splitter 2 contained 50 plates and was operated at a top temperature of 85°C and a bottom temperature of 160°C and under a pressure of 0.6 kg/cm²G. 50 percent by weight of N-methylpyrrolidone and 50 percent by weight of monoethylene glycol were blended and used as a solvent in the extraction unit 4, which comprised a 24-tray multi-stage extractor and which was operated at about 60°C.

The feed to splitter 2, which entered through line 1, was a catalytic reformate having the following composition and flow rate.

TABLE I

Component	Content (wt%)	Flow Rate (t/hr)
Benzene	4.1	3.8
Toluene	25.5	23.7
C ₈ aromatics	30.5	28.5
C ₉ aromatics	11.5	10.5
C ₁₀ aromatics	0.4	0.4
non-aromatics	28.0	26.0
Total	100.0	92.9

TABLE II

Component	Line 3		Line 16	
	Content (wt%)	Flow (t/hr)	Content (wt%)	Flow (t/hr)
Benzene	6.8	3.8	—	—
Toluene	42.3	23.7	—	—
C ₈ aromatics	4.7	2.6	70.0	25.9
C ₉ aromatics	—	—	28.4	10.5
C ₁₀ aromatics	—	—	1.1	0.4
non-aromatics	46.1	25.9	0.5	0.1
Total	100.0	56.0	100.0	36.9

The flow of solvent and solvent to feed ratio required in the extraction unit 4 according to the invention were compared with those by prior-art.

TABLE III

	Feed Charge (t/hr)	Solvent Rate (t/hr)	Extract Recycle Rate (t/hr)	Solvent/Feed Ratio
Invention	56.0	195	35	3.5
Prior-Art	93.0	392	78	4.2

It is thus obvious that the process of the invention can be carried out with far less solvent and less extract recycle than required by the prior-art process. The liquid-liquid extraction according to the invention was conducted at a solvent to feedstock (line 1) ratio of 2.1:1 and an extract - recycle to feed ratio of 0.4:1.

Line stream compositions provided from the second C₈ aromatics distillation column 17 were:

TABLE IV

Component	Line 18		Line 22	
	Content (wt%)	Flow (t/hr)	Content (wt%)	Flow (t/hr)
C ₈ aromatics	99.2	25.9	—	—
C ₉ aromatics	—	—	96.3	10.5
C ₁₀ aromatics	—	—	3.7	0.4
non-aromatics	0.8	0.02	—	—
Total	100.0	26.1	100.0	10.9

In the distillation column 17, C₈ aromatics were separated from C₉ and C₁₀ aromatics. Line stream 18, containing the majority of C₈ aromatics, was charged to the extractive distillation unit 19, which was equipped with 60 trays and which was operated at top temperature of 100°C, bottom temperature of 161°C, top pressure of 0.3 atmospheric absolute and bottom pressure of 0.6 atmospheric absolute, and in the presence of N-methylpyrrolidone solvent, the solvent to feed ratio being 3.1:1 and the flow of solvent being 80 t/hr.

The non-aromatics obtained as raffinate from the extractive distillation were withdrawn via line 21 and charged together with the stream in line 3 at a feed rate of 0.4 t/hr. of C₈ aromatics and of 0.2 t/hr. of non-aromatics to the extraction stage. The C₈ aromatics thus purified were withdrawn via line 20.

Table V below is provided to show the yield of each of the aromatics per feed in each strategic point of the process according to the invention in comparison with one prior-art.

TABLE V

Component	Invention						Prior-Art	
	Line 6		Line 20		Line 22		Line 6+20+22	Aromatics Extracts
	(A)	(B)	(A)	(B)	(A)	(B)	(A)	(B)
Benzene	100	3.5	—	—	—	—	100	3.8
Toluene	99.5	23.6	—	—	—	—	99.5	23.6
C ₈ aromatics	95.0	2.9	98.5	25.5	—	—	99.6	28.4
C ₉ aromatics	—	—	—	—	100	10.5	100	10.5
C ₁₀ aromatics	—	—	—	—	100	0.4	100	0.4
Total Recovery							99.7	66.7
Flow of solvent*	275(t/hr)						86.5	58.0
Solvent/feed ratio:	2.96						392(t/hr)	4.2

Note: (A) and (B) above denote, respectively, yield of designated aromatics by weight percent and rate of recovery thereof in tons per hour. *The flow of solvent according to the invention includes the amount of solvent supplied to the extractive distillation unit.

The C₉ aromatics fraction was processed in the hydrodealkylation unit 25, which was operated at an average reaction temperature of 560°C and a pressure of 60 kg/cm²G (865 psig), with a hydrogen to feed ratio of 11:1 and in the presence of chrome-alumina catalyst, thus hydrodealkylated and withdrawn via line 26 at the feed rate of 9.0 t/hr. and combined with the stream in line 6 to go into the aromatics fractionation system and thereby to add to the total yields of benzene, toluene and C₈ aromatics.

All aromatics shown in Table V as present in line 6 were fractionated in their respective fractionation columns and recovered as pure benzene, toluene and C₈ aromatics respectively, each substantially in 100 percent yield. The benzene was noted to have a crystallization point of 5.52°C. The toluene and C₈ aromatics were 99.5 percent and 99.0 percent, respectively, by gas-chromatography.

From the above exemplary embodiments it should be

noted that the process increases the yields of valuable aromatic hydrocarbons (e.g., C₈, C₉ and C₁₀) compared to the prior art at a saving in solvent used as reflected, for example, by reduced solvent to feed ratios in extraction unit 4. Further, the same solvent was used for both extraction and extractive distillation, further enhancing the economic viability of the instant process.

While the invention has been described and illustrated as to specific embodiments thereof, it will be understood that various changes and modifications may be made, which would be obvious to those skilled in the art, without departing from the spirit or scope of the appended claims.

We claim:

1. In a process for the separation and recovery of benzene, toluene and C₈ aromatic hydrocarbons from an aromatic hydrocarbon-rich charge stock selected from the group consisting of catalytic reformates, hydrogenated pyrolysis gasoline, crude benzole and mixtures thereof, which includes the steps of fractionating and solvent extraction, wherein the improvement, whereby enhanced yields particularly of C₈ aromatic hydrocarbons are obtained, comprises:
  - a. fractionating said aromatic hydrocarbon-rich charge stock to separately obtain
    - i. a first fraction containing substantially all of the benzene, toluene and non-aromatic hydrocarbons boiling in the same range and a minor amount of C₈ aromatic hydrocarbons,
    - ii. a second fraction containing substantially all of the C₈ aromatic hydrocarbons and non-aromatic

hydrocarbons boiling in the same range, and

- iii. a third fraction containing substantially all of the C₉ and C₁₀ aromatic hydrocarbons and other hydrocarbons boiling above the second fraction;

- b. subjecting the first fraction to liquid-liquid solvent extraction and recovering an aromatic extract;
- c. hydrodealkylating the third fraction to yield a product stream comprising benzene, toluene and C₈ aromatic hydrocarbons;
- d. combining said product stream of step (c) with said aromatic extract of step (b);
- e. fractionating the combined stream of step (d) to separate and recover substantially pure benzene, toluene, and C₈ aromatic hydrocarbons; and
- f. extractively distilling the second fraction of step (a) to separate and recover substantially pure C₈ aromatic hydrocarbons;

whereby C₈ aromatic hydrocarbons are recovered in an amount in excess of the amount of C₈ aromatic hydro-

carbons present in said aromatic hydrocarbons-rich charge stock.

2. The process as in claim 1 wherein said aromatic hydrocarbon rich charge stock is fractionated in step (a) by means of a splitter equipped with 50 plates which is operated at a top temperature of about 85°C. and a bottom temperature of about 160°C. under 0.6 kg/cm²G.

3. The process as in claim 1 wherein said second fraction is extractively distilled in step (f) by means of a dis-

tillation column operated at a top temperature of about 100°C. and a bottom temperature of about 160°C. under 0.3 atmospheric absolute at the top and 0.6 atmospheric absolute at the bottom.

5 4. The process as in claim 1 wherein said third fraction is hydrodealkylated in step (c) at temperatures in the range of 500°C. - 800°C., under pressures in the range of 35-76 kg/cm²G, and in the presence of hydrogen and chrome-alumina catalyst.
